(57) **CLAIM**

The ornamental designs for a three wheel motorcycle, as shown.

DESCRIPTION

FIG. 1 is a perspective view of one embodiment of the three wheel motorcycle of this invention;

FIG. 2 is a right elevation, in perspective, of the three wheel motorcycle of FIG. 1;

FIG. 3 is a rear elevation of the three wheel motorcycle of FIG. 1;

FIG. 4 is a top view, in perspective, of the three wheel motorcycle of FIG. 1;

FIG. 5 is a front view, in perspective, of the three wheel motorcycle of FIG. 1;

FIG. 6 is a bottom view of the three wheel motorcycle of FIG. 1;

FIG. 7 is a perspective view of a second embodiment of the three wheel motorcycle of this invention;

FIG. 8 is a right elevation, in perspective, of the three wheel motorcycle of FIG. 7;

FIG. 9 is a rear elevation of the three wheel motorcycle of FIG. 7;

FIG. 10 is a top view, in perspective, of the three wheel motorcycle of FIG. 7;

FIG. 11 is a front view, in perspective, of the three wheel motorcycle of FIG. 7; and,

FIG. 12 is a bottom view of the three wheel motorcycle of FIG. 7.
